BAG STRINGING NEEDLE

Edward E. West, Richmond, Va.

Application January 26, 1942, Serial No. 428,281

9 Claims. (Cl. 112—222)

This invention relates to improvements in stringing needles for stringing hemmed bags.

The principal object of the present invention is to provide stringing needles having improved means associated therewith for clamping strings therein to assure of the hemmed bags being accurately strung.

Another object is the provision of stringing needles having improved string gripping means thereon and cooperating means for guiding and assuring of the uniform and accurate clamping of the strings.

A further object is to provide stringing needles which constitute an improvement of the needles disclosed in my Patent No. 2,274,622.

These and other objects and advantages will be apparent as the specification is considered with the accompanying drawing, wherein:

Figure 1 is a perspective view of the bag stringing needles and a portion of the operating structure therefor;

Figure 2 is an enlarged side elevation of a modified form of stringing needles in string gripping position;

Figure 3 is a section on the line 3—3 of Figure 4, showing the needle in string receiving position;

Figure 4 is a section on the line 4—4 of Figure 2;

Figure 5 is a detached perspective of the cooperating needle shank member and sleeve, and the guiding means therefor;

Figure 6 is a side elevation of the preferred form of string needle shank member and sleeve, showing the needle in string gripping position;

Figure 7 is a section of the preferred form of needle, illustrated in Figure 6;

Figure 8 is a section on the line 8—8 of Figure 7;

Figure 9 is a side elevation of a further modified form of stringing needle shank member and sleeve, showing the needle in string gripping position; and

Figure 10 is a section of the modified form of needle, illustrated in Figure 9.

Referring more particularly to the drawing, wherein similar reference characters designate like parts throughout the several views, the numeral 1 denotes a stringing needle carriage of a bag stringing machine, not shown, for threading a pair of gripping needles and draw strings carried thereby through the hems of tobacco bags and the like, described and illustrated in my Patent No. 2,274,622, February 24, 1942. The stringing needle carriage 1 comprises a relatively flat, substantially rectangular needle saddle or plate

2 slidably sleeved on two, spaced, horizontally positioned, guide tracks 3, suitably fixedly connected at their outer ends in the top frame of the stringing machine, not shown.

5 The needles comprise two longitudinally extending substantially parallel, hollow sleeves 4, the inner ends of which are rigidly supported in a block or plate 5, suitably secured by screws 6 to the top of the needle saddle 2, and two pointed members 7 slidably arranged within the sleeves 4 and projecting through the forward ends thereof, for reciprocating movement relative thereto. The forward ends of the needle members 7, in the form illustrated in Figures 1 to 5, are pointed, as at 9, and these pointed ends are preferably cut away on the tops thereof, as at 10, to form string receiving openings or recesses having relatively flat, bottom and side string engaging walls 11 and 12, respectively. Reciprocation of the needle members 7, forwardly through the sleeves 4, moves the relatively flat rear walls 13 of the pointed needle members 7 away from and out of abutting engagement with the relatively flat forward ends 14 of the sleeves 4. The cut out portions 10 constitute string receiving openings for the insertion of draw strings 15. When the members 7 are moved rearwardly to closed or string gripping position, the relatively flat rear walls 13 thereof will engage with the flat forward ends 14 of the sleeves, and the strings 15 will be clamped in the openings or recesses 10, between the walls 12 and ends 14, respectively. As it is essential that the string receiving recesses 10 be disposed and retained in the upper faces of the needles at all times, in order to assure of the uniform and accurate positioning and gripping of the strings therein, vertically disposed, keys 16 are integrally formed on the lower portion of the members 7. The keys extend longitudinally and rearwardly from the walls 13 and are adapted to slidably fit within slots or keyways 17 in the underside and forward ends of the sleeves 4. Thus, during the reciprocation of the members 7 through the sleeves, the keys 16 thereof move within the slots 17 and the needle points 9 are prevented from rotating relatively with respect to the sleeves. This interconnecting means also has the advantage of strengthening the needle and preventing breakage thereof at the string receiving gap.

45 The needle saddle 2 is reciprocated forwardly and rearwardly on the guide tracks 3, to move the needles through the hems of a bag, by any suitable means, such as a vertically disposed lever, not shown, pivotally connected at its upper end

to an arm 18, in turn pivoted to the rear end of the saddle 2. The lever is rocked to reciprocate the saddle, through the medium of a cam, not shown, which operating mechanism is described and illustrated in my pending application, Serial No. 250,223, now issued in Patent No. 2,274,622.

The rear ends of the members 7 are fixed within a small block 18', mounted on the needle saddle 2 and movably connected by a pair of spring tensioned pins 19 to the saddle block 5, for slight sliding movement relative thereto. The block 18' is forwardly actuated, against the tension of spring 20, mounted on the pins 19, by any suitable means, such as a small cam 22 carried by one end of a crank 21, supported in a pair of journal blocks 23, secured to the rear end of needle saddle 2. The free end of the crank 21 is periodically actuated, by any suitable means, not shown, to force the cam 22 against and reciprocate the needle block 18', relative to the needle saddle 2, in an obvious manner.

When the end of a string is fed across the needles, the same is gripped, pulled out to the length necessary for service as a draw string, and cut or severed, by any suitable means not shown, such as that shown and described in my Patent No. 2,274,622, hereinbefore referred to. The two part needles then advance and carry the severed string section through the bag hems. While the string is being gripped and pulled to the necessary length, the needle saddle 2 and needles are being moved rearwardly along the guide tracks 3. With the string 15 extending across the needles, the saddle block 18' is moved forwardly, by the cam 22, and the members 7 are caused to slide forwardly through the needle sleeve 4 so that the rear walls 13 of the needle points 9 are moved away from, or out of engagement with the flat forward ends 14 of the sleeves. The tension of the springs 20 then moves the block 18' rearwardly and retracts the members 7 in the sleeves 4 so that the flattened rear ends 13 of the needle points 9 are moved into abutting engagement with the flattened forward ends 14 of the sleeves, and the string 15 is securely gripped or clamped between the ends 14 and walls 12 of the sleeves and string openings. The needle saddle is then moved forwardly, along the guide tracks 3, to carry the needle sleeves 4 and pointed members 7, in closed gripping position, through the hems of a bag. As the string 15 is gripped by the needles, during the feeding of the same through the bag hems, the string cannot slip through or be withdrawn from the needles and the bag hems are assured of being accurately and uniformly strung.

In the form of my needle, illustrated in Figures 6 and 7, the needle sleeves 4 are formed with pointed ends 26, and members 7 are slidably arranged therein. A relatively deep, transverse slot or recess 27 is formed in the sleeves 4, adjacent the pointed ends 26 thereof. The upper end of the slot is tapered and enlarged, as at 28, and the side wall 29 of the slot is substantially flat. Thus, when a string is extended across the needles, the same will be disposed within the slots 27, and when the needle shanks 7 are moved to closed position, upon the cam 22 moving the block 18' and members 7, the relatively flat forward ends 30 of the members 7 will engage the string and the latter will be securely clamped, between the ends 30 and walls 29. It will, of course, be understood that in this embodiment the crank 21 will be periodically actuated to force the cam 22 against the needle block 18', to reciprocate the

latter against the needle saddle 2, to push the members 7 forwardly to grip the string within the slots 27. In other words, the cam 22 functions to move the members 7 to closed gripping position, whereas in the form, illustrated in Figures 1 to 5, the cam actuates the members 7 to open position.

In the modification of the needle shown in Figures 9 and 10, wherein the needle sleeves 4 are provided with the pointed ends 26. A substantially U-shaped, transverse slot 31 is formed in the sleeves 4 to the rear of the pointed ends 26 thereof, of which slot 31 is adapted to coact with a corresponding substantially U-shaped transverse slot 32, in the members 7, adjacent their forward ends, to receive a string. The slots 32 in the members 7 are aligned with the slots 31 in the sleeves so that, when the string is fed across the needles, the string will enter and be disposed within the slots 31 and 32. Movement of the needles to closed gripping position, in the same manner as the needle movement of the modification illustrated in Figures 6 and 7 causes one wall of each slot 32 to bear against the string and clamp the latter against the corresponding wall of the sleeve slot 31. Thus the strings are uniformly and securely clamped in the needles.

Having thus described my invention what I claim is:

1. A bag stringing needle mechanism of the character described having a pair of stringing needles, each of said needles comprising a shank portion and a cooperating longitudinally and centrally bored pointed tube sleeved over said shank portion, said tubes each having a string receiving groove therein, one wall of which has a substantially flat face in axial alinement with the bore of the tube, said grooves substantially intersecting and communicating with the bores of said tubes and means for moving said shank portions through said cooperating sleeved tubes, the ends of said shank portions cooperating with said flat faces of said string receiving grooves for clamping a string therein.

2. A bag stringing needle mechanism of the character described having a pair of stringing needles, each of said needles comprising a shank portion and a cooperating centrally bored pointed tube sleeved over said shank portion, said tube having a string receiving groove in the upper face thereof, one wall of the groove being substantially flat and in axial alinement with said bore, the end of said shank portions being substantially flat and movable into said groove and engageable with the strings for clamping the latter therein against said flat wall.

3. A bag stringing needle mechanism of the character described comprising a pair of stringing needles, each of said needles comprising a shank portion and a cooperating pointed longitudinally bored tube sleeved over said shank portion, said tube having a relatively deep string receiving slot in the upper face thereof and extending a considerable distance into said bore, said slot having a substantially flat wall in axial alinement with the said bore the ends of said shank portions being movable through said bores into said slots and engageable with the strings for clamping the latter therein against said substantially flat walls.

4. A bag stringing needle mechanism of the character described having a pair of stringing needles, each of said needles comprising a shank portion and a cooperating centrally bored tube sleeved over said shank portion, said tube and

shank portion having laterally extending string receiving grooves therein aligned with each other and communicating with said bore, and automatic intermittently actuated means for moving said shank portions through said cooperating tubes for clamping a string in said string receiving grooves.

5. A bag stringing needle mechanism of the character described having a pair of stringing needles, each of said needles comprising a shank portion and a centrally bored cooperating pointed tube sleeved over said shank portion, said tube and shank portion having substantially U-shaped string receiving slots therein adjacent but rearwardly of their front ends, and means for moving said shank portions through said cooperating tubes to bring said slots into substantial alignment with each other and for clamping a string therein.

6. A bag stringing needle mechanism of the character described having a pair of stringing needles, each of said needles comprising a shank portion and a centrally bored cooperating tube sleeved over said shank portion, said tube having a needle point formed with a string receiving groove therein, said groove extending transversely through the upper portion of the tube and extending substantially through and terminating at its base in the bore of the tube, automatic intermittently actuated means for moving said shank portions through said cooperating sleeved tubes, said groove having an end wall rearwardly of said needle point and said wall having a flat portion axially aligned with the bore of said tube, and means on said shank portions cooperating with said string receiving grooves for clamping a string therein and against the flat portions of said walls.

7. A bag stringing needle mechanism of the character described having a pair of stringing needles, each of said needles comprising a shank portion and a centrally bored cooperating pointed tube sleeved over said shank portion, said tube and shank portions each having a cooperating string receiving groove therein, and means for moving said shank portions through said cooper-

ating tubes to bring said grooves into alignment and for clamping a string in said cooperating aligned string receiving grooves.

8. A bag stringing mechanism of the character described comprising needle mechanism for inserting a string into the hem of a bag and comprising a string carrying needle consisting of a shank portion, and a centrally bored cooperating tube sleeved over said shank portion, said tube having a needle point and formed with a transverse string receiving groove therein communicating with and terminating at its base in the bore of said tube, said groove having a flat outer end wall, axially aligned with the bore of said tube, and automatically intermittently actuated means for moving said shank portion through said cooperating tube and means on said shank portion cooperating with said flat outer end wall of said string receiving groove for clamping a string against said wall.

9. A bag stringing mechanism of the character described comprising needle mechanism for inserting a string in the hem of a bag and comprising a string carrying needle consisting of a shank portion and a cooperating centrally bored tube sleeved over said shank portion, said shank portion having a substantially flat string gripping surface adjacent its forward end, said tube having a needle point and formed with a transverse string receiving groove having its base in the wall of the tube in intersecting relation to the bore thereof, said transverse groove having a string gripping surface cooperating with the string gripping surface on said shank portion, automatically operative means for jointly shifting said members into and out of the hem and in timed relation therewith relatively shifting said shank portion and tube to grip the string between the string gripping surface of the shank and the string gripping surface of said transverse groove prior to the passage of the needle into the hem of the bag and for releasing said string after the passage of the needle into the hem.

EDWARD E. WEST.
